UNITED STATES PATENT OFFICE

CHAUNCEY W. B. HUGHES, OF MARION, INDIANA

DESIGN FOR A BOTTLE

Application filed July 11, 1931. Serial No. 40,504. Term of patent 14 years.

To all whom it may concern:

Be it known that I, CHAUNCEY W. B. HUGHES, a citizen of the United States, residing at Marion, in the county of Grant and State of Indiana, have invented a new, original, and ornamental Design for Bottle, of which the following is a specification, reference being had to the accompanying drawings, forming a part hereof.

I claim:

The ornamental design for a bottle, as shown.

CHAUNCEY W. B. HUGHES.
